Primary Examiner—Charles A Rademaker*Assistant Examiner*—Carissa C Fitts*(74) Attorney, Agent, or Firm*—Pillsbury Winthrop Shaw Pittman LLP(57) **CLAIM**

The ornamental design for a flashlight, as shown and described.

DESCRIPTION

FIG. 1 is a front elevation of a flashlight showing our new design;

FIG. 2 is a rear elevation view thereof;

FIG. 3 is a right side view thereof;

FIG. 4 is a left side view thereof;

FIG. 5 is a top plan view thereof;

FIG. 6 is a bottom plan view thereof;

FIG. 7 is a perspective view thereof with legs in an extended configuration; and,

FIG. 8 is a perspective view thereof.

Where included, broken lines showing environment or structure are for illustrative purposes only and form no part of the claimed design.
